UNITED STATES PATENT OFFICE.

SIMON COOPER, OF BROOKLYN, NEW YORK, ASSIGNOR TO MENASHA WOODEN WARE CO., OF MENASHA, WISCONSIN, A CORPORATION OF WISCONSIN.

SEALING MACHINE.

Application filed November 21, 1919. Serial No. 339,757.

To all whom it may concern:

Be it known that I, SIMON COOPER, a citizen of the United States, residing at Brooklyn, in the county of Kings and State 5 of New York, have invented certain new and useful Improvements in Sealing Machines, of which the following is a specification.

The subject of the present invention is a 10 machine for applying sealing wires to pails and other containers.

The objects of the invention are to provide a simple, practical and efficient machine for the purpose stated.

15 In the accomplishment of these objects, I employ in combination with means for supporting and holding the pails, mechanism for severing the sealing wires into lengths and for pointing the ends of such lengths 20 towards the supported pail and for then driving such ends into the body of the pail. The invention embodies also other features such as means for upsetting or securing the 25 ends of the inserted wires at the inside of the pail, all of which will appear as the specification proceeds.

In the drawings accompanying this specification, I have disclosed the invention embodied in a concrete, practical form but 30 wish it understood that the structure may be modified in various respects without departure from the true spirit and scope of the invention, as defined in the appended claims. I would also have it understood 35 that the terms which I have employed are used in a descriptive rather than in a limiting sense, except as may be required by the prior art.

In the drawings referred to, Figure 1 is a 40 top plan view of the machine with parts broken away and other parts shown in section.

Figure 2 is a vertical sectional view of the 45 machine taken substantially on the plane of the line 2-2 of Figure 1.

Figure 3 is an enlarged and broken top plan view of one of the wire bending and driving devices.

Figure 4 is a side elevation thereof.

Figure 5 is a broken and partly sectional 50 view of the head portion of the machine, involving the wire hooking and riveting devices.

Figures 6 and 7 are enlarged broken detail views of one of the wire hooking de- 55 vices.

Figures 8 to 12 illustrate successive steps in the operation of applying and using the sealing wires.

The machine embodies, first, a holder or 60 support for the pail being operated upon. This holder I have shown in the form of a head 15 (Figure 2) against which the pail 16 is pressed by a plunger head 17. A pedal lever 19 is operatively connected to the 65 plunger head 17 by a shaft 18' and surrounding this shaft 18' is a spring 18 which yieldingly holds the plunger head 17 in a raised position.

The wire from which the seals are made 70 is indicated at 20, two separate lengths of such wire being shown, each length being fed into the machine by a wire feeding device, embodying in each instance a carriage 21 sliding on the guides 22, said carriage 75 carrying relatively fixed and movable wire gripping jaws 23 and 24, the latter being carried by a bell-crank lever 25 pivoted on the carriage at 26 and connected with one end of a link 27 whose other end is connected with a lever 28, which in turn is connected with a lever 29 (see left hand side of Figure 1) which is operated by a cam 30 on the cam shaft 31. The two wire feeders are similar in construction, it being 80 understood that the wire feeding device at the right in Figure 1 may be operated by means similar to that disclosed for the feeder at the left side of the machine. The wires are advanced by these feeding devices 85 through guides 32 into position to be taken by the wire bending and driving devices now to be described.

Four of the wire bending and driving 90 devices are provided in the machine illus- 95 trated, grouped radially about the pail-

holder and operating in pairs to bend and drive into the pail the opposite ends of the two lengths of wire cut from the two sources of wire supply. Referring particularly to Figures 1, 3 and 4, it will be seen that these devices comprise in each instance, a slide 33 working in guides 34, said slides reciprocating substantially radially of the pail-holder and carrying at the inner end thereof 10 of a device for gripping and bending the wire. This device, is shown as a fixed block or former 35 on the lower face of the slide and an arcuate bending arm 36 carried by the lower end of the shaft 37 and arranged 15 to bend the end portion of the wire about the stationary former. This bender shaft has secured to its upper end a lever or arm 38 to which one end of a toggle is pivoted at 39. The two levers, constituting the 20 toggle are designated 40 and 41, the first of these being pivoted to the bender arm at 39 and the second being pivoted to the rearward end of the slide at 42. These toggles are operated, in each instance, by a link 43 25 pivoted at one end to the joint of the toggle at 44 and connected at its opposite end with a rocker arm 45. These rocker arms are secured on the upper ends of the rock shafts 46 and 47. Rock shafts 46, in the machine 30 illustrated, receive motion from the cams 47' on the cam shaft 31 through the medium of levers 48 carrying rollers 49 engaging the grooves in said cams and rock shafts 47 receive their motion from the rock shafts 35 46 through the medium of the intermeshing gear segments 50 and 51 on their respective shafts. From this it will be apparent that the four toggles are made and broken substantially simultaneously. Adjustable stops 40 are shown provided at 52 to prevent movement of the toggles past the centers. In Figures 3 and 4 the toggle is shown in the "broken" condition, in which the bending jaw is thrown open and it will be apparent 45 that as the toggle is made or straightened the jaw will operate to bend the end of the wire about the former, in the manner indicated, so that the projecting point of the wire will stand substantially radial with 50 respect to the center of the pail on the pail-support. Also in these views there is shown a guiding member 53, for directing the wire into the bight of the bending jaw.

The wires are severed in proper lengths 55 by means consisting in the present disclosure of the wire cutter blades 54 (Figure 1) carried by rock shaft 55 which are operated by arms 56 connected by links 57 (Figure 2) with the arms 58 of bell-crank levers pivot- 60 ed at 59 and whose other arms 60 are actuated by suitable cams on the cam shaft 31. The cutters described are constructed to point the wire ends in the act of severing the wire.

65 After the ends of a length of wire have

been caught by the bending devices of two of the adjacent slides (those at the right or at the left in Figure 1) and bent inward toward the pail, as shown, the two slides are bodily advanced to drive the inwardly directed points of the wire into the body of the pail. The means for thus advancing the slides comprises the arms 61 pivotally mounted on the lower ends of rock shafts 70 46 and 47 connected at one end by the links 62 with the slides, while the opposite end of each of the arms 61 is connected to the links 63.

The movement of these slides is sufficient to drive the inwardly bent ends of the wire 80 in through the wall of the pail, as indicated in Figure 8. The projecting ends of the driven wires are then curled over, as indicated at 64 in Figure 9, after which the curled or bent over ends of the wire are 85 flattened down and driven back into the wall of the pail, as indicated at 65 in Figure 10.

The means for curling or bending over the projecting ends of the wires are illustrated more fully in Figures 5, 6 and 7 90 and consist in each instance of a pair of spaced abutments or pins 66 and 67 between which the end of the wire is driven, the first of said pins being concentric with the shaft 68 which carries it and the second pin is 95 eccentric thereto so that in the rotation of said shaft the eccentric pin will wrap the projecting end of the wire about the concentric pin substantially as indicated in Figure 7. Four of these wire curling devices 100 are provided in the present disclosure, the same being mounted in guides 69 on the head of the machine and being driven rotarily by pinions 70 on the upper ends of the curling shafts 68 in mesh with a gear 71 on 105 the central shaft 72.

The shaft 72 is oscillated, in the machine illustrated, from a cam 73 on cam shaft 31 through the medium of a cam actuated lever 74 which is secured to the lower end of a shaft 75, whose upper end carries a lever 76 connected by a link 77 with an arm 78 on the upper end of shaft 72.

The curling devices are retracted to permit of the final riveting action by means 115 consisting in the present disclosure of a cam 79 fast on the central shaft 72 and engaged by cam-rolls 80 on the shifter ring 81, in which the upper ends of the curler shafts 68 are rotatably held. The cam is so constructed and the parts are so arranged that after the completion of the curling operation (Figure 7), the further rotary movement of the central shaft 72 will cause the curlers to be retracted from the pail. The gear 71 120 may be of "interrupted" or mutilated construction to permit of this further rotary movement of the central shaft for the retraction of the curlers, the curlers then being withdrawn without rotary movement. 125

The pail is centered and supported at the top, in the machine shown, by a frame or head 82 on the lower end of shaft 72 and which fits into the upper end of the pail as the same is raised by plunger head 17. This supporting head is also here utilized for flattening down the projecting wire ends, it being shown as provided for the purpose, with the anvil or presser shoulders 83 which, when the wire ends are driven inward stand to one side of such ends (Figure 6) and which in the rotation of the shaft 72 are caused to override the curled wire ends (Figure 7) to flatten the same down and drive the points back into the wall of the pail, as shown in Figure 10.

The present machine is controlled so as to stop after the performance of a complete cycle of operations, a one-revolution clutch being provided for this purpose, as indicated at 84 in Figure 1 (right hand end of figure), said clutch being mounted on the drive shaft 85 which carries at its opposite end the drive pulley 86. This clutch is controlled by a lever 87 (Figure 2) pivoted at 88 and having an arm 89 carrying a roll 90 in engagement with cam 91 on the cam shaft 31. Clutch lever 87 is also shown provided with an upstanding arm 92 to which there is connected a control rod 93.

In operating the machine, the foot pedal 19 is first depressed to lower the presser head 17. After placing a pail on said presser head, the pedal is released and the pail is thereupon raised by the presser head into engagement with the fixed head 15, it being centered thereon by the anvil-carrying member 82. The handle rod 93 is thereupon actuated to trip the one-revolution clutch. Motion from the drive shaft 85 is thereupon imparted to cam shaft 31 through the medium of gears 94 and 95. The wire feeding devices are thereupon caused to advance, and to feed the proper lengths of wire into the grip of the wire benders on the slides.

The wire cutters thereupon operate to sever the predetermined lengths of wire and to point the ends thus severed. The wire benders then operate to turn the ends of the cut wires inwardly toward the center of the pail, as shown in Figure 1, after which the slides advance and drive the ends of the wire in through the wall of the pail, as in Figure 8. The wire curlers then operate, as shown in Figures 6 and 7, to curl the inwardly projecting ends of the wires, after which the curlers are retracted and the anvils rotate to flatten down the curled ends of the wire, driving the points of the wires into the material of the pail, as in Figure 10. The ends of the wires are thus firmly anchored in the material of the pail, leaving loops or stretches 96 of wire at the opposite sides of the pail which can be turned up over the pail cover, as indicated in Figure

12, and then twisted, as at 97, to secure and seal the cover in position.

What I claim is:

1. In a machine of the character described, a pail-holding device, means for cutting a measured length of wire, means for bending the ends of said measured length of wire radially toward the center of a pail on the pail-holding device the terminal ends of said bent wire ends projecting beyond the bending means and means for advancing said bending means for driving said bent ends of the wire into the pail thus held. 70

2. In a machine of the character described, a pail-holding device, a wire feeder, a wire cutter, wire bending devices arranged to receive the cut length of wire and to bend the opposite ends of the same radially toward a pail on the pail-holding device the terminal ends of said wire projecting beyond the bending devices and means for advancing the bending devices for driving said bent ends of the cut wire into the wall of the pail thus held. 80

3. In a machine of the character described, a pail-holding device, a wire feeder, a wire cutter, wire bending devices arranged to receive the cut length of wire and to bend the opposite ends of the same radially toward a pail on the pail-holding device, the terminal ends of the wire projecting freely beyond the bending devices, means for advancing the bending devices for driving said bent ends of the cut wire into the wall of the pail thus held and means for turning over the ends of the wire at the inside of the pail. 95

4. In a machine of the character described, a pail-holding device, a wire feeder, a wire cutter, wire bending devices arranged to receive the cut length of wire and to bend the opposite ends of the same radially toward a pail on the pail-holding device, the terminal ends of the wire projecting freely beyond the bending devices, means for advancing the bending devices for driving said bent ends of the cut wire into the wall of the pail thus held, means for curling the projecting ends of the inserted wire at the inside of the pail and means for driving the points of said curled ends back into the wall 100 of the pail. 110

5. In combination, a pail-holding device, means for driving wire ends through the wall of a pail held by said device, means for rebending the projecting portions of said wire ends and rotary means arranged within the pail for driving the rebent ends back into the wall of the pail. 120

6. In combination, a pail-holding device, means for driving wire ends through the wall of a pail held by said device, means for curling over the projecting portions of said driven wire ends and rotary means arranged within the pail for driving the curled ends back into the wall of the pail. 125

7. In combination, a pail-holding device, means for driving wire ends through the wall of a pail held by said device, means for curling over the projecting portions of said driven wire ends and rotary means for forcing the points of said curled wire ends back into the wall of the pail. 70
8. In combination, means for driving wire ends through the wall of a pail, means for curling over the projecting portions of said wire ends and rotary means within the pail for forcing said curled wire ends back into the wall of the pail. 75
9. In combination, means for pointing the end of a wire, means for forcing said pointed wire end through the wall of a pail, means for curling the projecting portion of said pointed wire end and rotary means arranged within the pail for driving the point of said curled end back into the wall of the pail. 80
10. In combination, means for pointing the ends of a wire, means for bending the opposite ends of said pointed wire toward the center of a pail with the ends of the wire projecting freely beyond the bending means and means for bodily advancing the bending means for driving said pointed ends of the cut wire into the wall of the pail. 85
11. In combination, means for serving a predetermined length of wire, means for radially bending the ends of said cut wire toward the center of a pail, means for driving said bent ends of the cut wire through the wall of the pail, means for bending the projecting portions of the wire ends and rotary means for driving said bent projecting end portions of the wire back into the wall of the pail. 90
12. In combination, means for angularly severing the ends of a length of wire, means for bending the ends of said cut wire toward the center of a pail, means for driving said bent ends through the wall of the pail, means for redirecting the projecting wire ends within the pail and rotary means within the pail for driving the redirected wire portions into the wall of the pail. 95
13. In combination, means for obliquely severing the ends of a length of wire, means for bending the ends of said cut wire toward the center of a pail, means for driving said bent ends of the wire into and through the wall of the pail, means for redirecting the projecting wire ends within the pail and means for forcing the redirected portions of the wire back into the wall of the pail. 100
14. In combination, means for releasably holding a pail, means for driving the opposite ends of a length of wire through the wall of the pail thus held, means for curling over the inwardly projecting portions of the wire ends, and means for forcing said ends back into the wall of the supported pail. 105
15. In combination, a pail-holder, a wire bender for bending the end of a wire toward the center of a pail on the pail-support and means for radially advancing the wire bender to drive the bent end of the wire into the pail. 110
16. In combination, a pail-holder, a radially actuated wire driving slide, a wire bender on said slide, a toggle for operating said wire bender and lever for bodily oscillating the slide. 115
17. In combination, a pail-holder, a slide operating substantially radially of said pail-holder, a wire bender on said slide for bending a wire substantially radially of the pail-holder and means for operating said slide to force the ends of the bent wire into the wall of the supported pail. 120
18. In combination, a pail-holder, a slide operating substantially radially of said pail-holder, a wire bender on said slide for bending a wire substantially radially of the pail-holder, means for operating said wire bender and means for thereafter advancing the slide toward the pail-holder to force the ends of the bent wire into the wall of the supported pail. 125
19. In combination, a work-holder, a radially movable slide, means for advancing a wire to said slide, formers on the slide for bending the end of the wire radially toward the work and means for advancing the slide to force the end of the bent wire into the wall of the supported pail. 130
20. In combination, a pail-support, wire feeding means, bending devices adapted to receive and radially bend, towards the pail, the ends of the wires advanced by the feeding means, means for bodily reciprocating the wire bending devices substantially radially of the pail-support and means for serving the wires advanced to the bending devices. 135
21. In a machine of the character described, a reciprocating slide, a wire bender mounted on said slide, a toggle connected at one end with the slide and at the opposite end with said wire bender and an operating element connected with the joint of the toggle. 140
22. In a machine of the character described, a reciprocating slide, a wire bender mounted on said slide, a toggle connected at one end with the slide and at the opposite end with said wire bender, an operating element connected with the joint of the toggle and means for reciprocating the slide independently of said operating element. 145
23. In a machine of the character described, a reciprocating slide, a wire bender mounted on said slide, a toggle connected at one end with the slide and at the opposite end with said wire bender, an operating element connected with the joint of the toggle and means for reciprocating the slide independently of said operating element, 150

- 5 said operating means including a rock shaft, a rock arm on said shaft connected with the operating element and a second rock arm on said shaft having a connection with the slide.
24. In combination, a pail-holder, means for driving wire ends through a pail on said holder, means for curling the projecting portions of the driven wire ends and means for advancing and retracting said curling means into and out of a pail on the holder. 10
25. In combination, a pail-holder, means for driving a plurality of wire ends through a pail on said holder, a plurality of rotary curling devices for curling the projecting portions of said wire ends and means for advancing and retracting all of said wire curlers into and out of a pail on the holder. 15
26. In combination, a pail-holder, a shifter movable toward and away from said pail-holder and a plurality of rotary wire curling devices mounted on said shifter. 20
27. In combination, a pail-holder, a plurality of shafts movable longitudinally toward and away from said pail-holder, rotary wire curling devices on said shafts, a shifter engaged with said shafts and means for operating said shifter. 25
28. In combination, a pail-holder, a plurality of shafts movable longitudinally toward and away from said pail-holder, rotary wire curling devices on said shafts, a shifter engaged with said shafts and means for operating said shifter including a movable cam and connections between the cam and shifter. 30
29. In combination, rotary wire curlers, gearing for simultaneously operating the same, a pail-holder and means for simultaneously advancing and retracting the wire curlers with respect to the pail-holder. 40
30. In combination with a pail-support, a shaft arranged concentrically thereof, a gear on said shaft, wire curlers grouped about said shaft and provided each with a pinion in mesh with the gear, means for oscillating said shaft and means operable by said oscillation of the shaft for advancing and retracting the wire curlers with respect to the pail-holder. 45
31. In combination with a pail-support, a shaft arranged concentrically thereof, a gear on said shaft, wire curlers grouped about said shaft and provided each with a pinion in mesh with the gear, means for oscillating said shaft and means operable by said oscillation of the shaft for advancing and retracting the wire curlers with respect to the pail-holder and wire shaping means carried by said shaft and arranged to project within a pail on the pail-holder. 55
32. In combination, a pail-holder, a rotary shaft disposed concentrically thereof, wire flattening devices carried by said shaft, 60
- means for driving wire ends through the wall of a pail on the pail-support at one side of the wire flattening devices and means for operating the shaft to carry the wire flattening devices over the projecting portions of the wire ends. 70
33. In combination, a pail-support, rotary actuated wire flattening devices engageable within a pail on the pail-support, wire curling devices, means for operating said wire curling devices to bend the ends of wires projecting within the pail and means for then rotatably operating the flattening devices to drive the bent wire ends back into the pail. 75
34. In combination, a pail-holder, wire curlers, means for advancing and retracting said curlers with respect to a pail on the pail-support, wire flatteners arranged within a pail on the pail-support and means for operating the wire flatteners after the retraction of the wire curlers. 80
35. In combination, a pail-support, a shaft disposed concentrically thereof, a head on the end of said shaft provided with spaced wire flattening anvils, means for driving wire ends through the wall of a pail on the pail-holder in the spaces between the anvils and means for rotating the shaft to carry the anvils over the projecting portions of the wire ends. 85
36. In combination, a pail-support, a wire bender, a shaft concentric to the pail-support, a wire flattening device carried by said shaft, means for oscillating said shaft, operating connections from the shaft for driving the wire bender and cam mechanism operated by said shaft for advancing and retracting the wire bender with respect to the pail-support. 90
37. In combination, a pail-holder, means for driving the end of a wire through a pail on said holder, a wire bender having spaced abutments disposed to receive between them the projecting end of such wire and means for rotating said abutments to curl the projecting end of the wire. 100
38. In combination, a pail-holder, means for driving the end of a wire through a pail on said holder, a wire bender having spaced abutments disposed to receive between them the projecting end of such wire, means for rotating said abutments to curl the projecting end of the wire, an anvil disposed at one side of the projected wire end, means for retracting the abutments after the curling operation and means for advancing said anvil over the curled wire end. 110
39. In combination, a head, a plunger for holding a pail engaged with said head, a centering device carried by said head and arranged to enter a pail engaged therewith, means for driving wire ends in through the wall of said pail and means 125
- 130

for operating said centering device to flatten the projecting portions of said wire ends against the inner wall of the pail.

40. In a machine for applying sealing wires, the combination of wire feeders, wire cutters, wire clamps, means for initially operating said clamps to bend portions of the

wire with the terminal ends thereof projecting beyond the clamps and subsequent operating means for said clamps for driving 10 the projecting ends of the wire.

In testimony whereof I affix my signature.

SIMON COOPER.
